US00D692476S

(12) **United States Design Patent**
Lee

(10) **Patent No.:** US D692,476 S
(45) **Date of Patent:** ** Oct. 29, 2013

(54) **TYPE FONT**

(75) Inventor: **Yeon Hee Lee**, Seoul (KR)

(73) Assignee: **Hyundai Motor Company**, Seoul (KR)

(**) Term: **14 Years**

(21) Appl. No.: **29/410,957**

(22) Filed: **Feb. 20, 2012**

(30) **Foreign Application Priority Data**

Nov. 16, 2011 (KR) 30-2011-0048284

Nov. 16, 2011 (KR) 30-2011-0048285

Nov. 16, 2011 (KR) 30-2011-0048288

(51) **LOC (9) Cl.** **18-03**

(52) **U.S. Cl.**

USPC **D18/24**

(58) **Field of Classification Search**

USPC D18/24-33; 101/398, 399; 400/484
